His Attorney.

UNITED STATES PATENT OFFICE.

FRITZ BAHR, OF BERLIN-CHARLOTTENBURG, GERMANY, ASSIGNOR TO GENERAL ELECTRIC COMPANY, A CORPORATION OF NEW YORK.

TUNGSTEN ARC LAMP.

Application filed May 14, 1924, Serial No. 713,361, and in Germany August 4, 1923.

My invention relates to tungsten arc lamps in which the arc is started by separating the electrodes. More in particular the invention relates to that type of tungsten arc in which a bimetallic strip is used to cause the separation of the electrodes. In tungsten lamps of the foregoing character, strips of this sort are connected in the supporting stem of the anode in the circuit over which the current passes and consequently become heated by the flow of the current. The tungsten electrode is so connected to the bimetallic strip and the strip so arranged that when the bimetallic strip bends the anode is separated from the cathode and the arc is established. It frequently occurs, when the usual form of bimetallic strip is used, that sufficient distortion does not take place to separate the electrodes when the current is turned on. This is especially the case in lamps that use a small amount of current.

One of the objects of my invention is to provide a bimetallic strip of such construction as to insure a sufficient degree of bending and thereby insure a more reliable operation of the lamp even when a small amount of current is used. This is accomplished, for example, by increasing the length of the path of the current over the bimetallic element by making the element in a zigzag form. It is also an object to provide an improved arrangement for increasing the stability of the supporting wire stem by holding the loops of the bimetallic strip together with one or more clamps of suitable insulating material.

To accomplish the foregoing, I make use of means hereinafter more fully set forth and claimed, reference being had to the accompanying drawing.

In Fig. 1 of the drawing, there is shown one example of construction of a tungsten lamp made in accordance with the principles of my invention; in Fig. 2 the bimetallic element is shown in side view, and in Fig. 3 the bimetallic strip is shown in a position similar to that of Fig. 2 with the supporting clamps, one at the upper end and one at the lower end.

Referring more in detail to the drawing, it will be seen that the lamp comprises a glass envelope *a* similar to that used in the ordinary incandescent lamp. The lamp also

comprises a screw base *b* and a glass stem *c* through which stem the leading-in wires *d* pass that form the supporting stems *e* of the two electrodes *f* that rest in contact when the lamp is not in use. Into the supporting stem of the anode is inserted the bi-metallic zigzag strips *g*, folded at the points *g'* as shown. The loops *g'* of the bimetallic strip are clearly shown in Fig. 2.

The folds of the bimetallic strips are supported on the sides by suitable insulating plates *h* of mica, for example, which may be clamped into position in any suitable manner. With this arrangement the loops of the strip are given greater stability.

I have shown in the drawing a bimetallic strip in the anode stem. It will be understood however that a similar bimetallic strip may be inserted in each one of the wire stems. Furthermore, if the lamp is provided with two electrodes, a bimetallic strip may be provided for each electrode.

While I have shown a bimetallic strip with only two loops, it will be understood that a number of loops may be varied.

It will be further understood that while I have shown and described specific embodiments of my invention, I do not wish to be limited to these specific constructions inasmuch as other variations will readily suggest themselves which may be made without departing from the spirit of my invention and without departing from the scope of my claims.

What I claim as new and desire to secure by Letters Patent of the United States, is,—

1. An arc lamp provided with a bimetallic element for separating one of the electrodes from another when an electric current is sent through the element, said element being folded into a plurality of loops and means for reinforcing the folds of the element.

2. An arc lamp provided with a bimetallic element for separating one of the electrodes from another when an electric current is sent through the element, said element being folded into a plurality of loops, and means for holding the folds of the element in alignment.

In witness whereof, I have hereunto set my hand this 16th day of April, 1924.

FRITZ BAHR.
